[57] CLAIM

The ornamental design for a combined dual desk, wall panel and storage unit, as shown and described.

DESCRIPTION

FIG. 1 is a front perspective view of the combined dual desk, wall panel and storage unit showing my new design;

FIG. 2 is a top plan view thereof;

FIG. 3 is a bottom plan view thereof;

FIG. 4 is a front elevational view thereof; and,

FIG. 5 is a rear elevational view thereof.

FIGS. 1 and 3-5 are stippled shaded to show color contrast.
